US0D1097566S

(12) United States Design Patent (10) Patent No.: US D1,097,566 S
(45) Date of Patent: * Oct. 14, 2025

(54) LUGGAGE

(71) Applicant: JRSK, Inc., New York, NY (US)

(72) Inventors: Cuan Hanly, Brooklyn, NY (US);
Luigi Auricchio, Brooklyn, NY (US);
Isaac Krady, Oakhurst, NJ (US);
Diana Ong, Brooklyn, NY (US); Peter Lengel, Brooklyn, NY (US)

(73) Assignee: JRSK, Inc., New York, NY (US)

() Term: 15 Years

(21) Appl. No.: 29/993,898

(22) Filed: Mar. 18, 2025

Related U.S. Application Data

(62) Division of application No. 29/880,862, filed on Jul. 28, 2023.

(51) LOC (15) Cl. 03-01

(52) U.S. Cl.
USPC D3/279
